Rosenbaum, Stockbridge, Attorneys

ATTORNEY.

UNITED STATES PATENT OFFICE.

FREDERICK O. WINKLEHAUS, OF NEW YORK, N. Y., ASSIGNOR TO METROPOLITAN ELECTRIC MANUFACTURING COMPANY, A CORPORATION OF NEW JERSEY.

SAFETY SWITCH

1,417,650.

Specification of Letters Patent. Patented May 30, 1922.

56

Application filed August 14, 1919. Serial No. 317,523.

To all whom it may concern.

Be it known that I, FREDERICK O. WINKLEHAUS, a citizen of the United States, residing at the city of New York, in the borough of Queens, and State of New York, have invented certain new and useful Improvements in Safety Switches, of which the following is a full, clear, and exact description:

10. My invention pertains to switch and fuse boxes for electrical installations, and particularly those boxes which permit of inspection and renewal of fuses, but prevent access to the interior of the boxes until the 15 switch has been first placed in the "off" position, whereby the person making the inspection or renewal is not in danger of an electrical shock.

An object is to improve and simplify such 20 devices, making them more reliable, easier and cheaper to manufacture, and which will not need frequent attention in operation.

More particularly, an object is to provide 25 a switch for such boxes which has a quick break, to prevent sparking, and which is readily adaptable to this type of box.

Another object is to provide an improved bearing for the switch operating mechanism and handle which is simple, and efficient in 30 construction, and of low manufacturing cost.

In the drawings:

Fig. 1 is a plan view of an embodiment 35 of my invention;

Fig. 2 is a partial side elevation showing the operating handle and "knock-out" bearing member;

Fig. 3 is an elevation, some of the parts being broken away to better show the interior construction, the switch being shown 40 in the "on" position;

Fig. 4 is a view similar to Fig. 3, but showing the switch in the "off" position, and the cover released;

Fig. 5 is a cross sectional view taken substantially on the line 4-4 of Fig. 3, certain 45 of the parts being broken away;

Fig. 6 shows two views of the "knock-out" bearing for the switch handle;

Figs. 7 and 8 show views of certain details of construction.

The device consists of a main casing or box 1, of any suitable material, preferably metal, having a fixed cover portion 2, and 55 movable cover portions 3 and 4. The mov-

able cover portions are hinged in any suitable manner to the fixed cover portion, as by hinges 5.

The switch handle 6 is located exteriorly of the casing and mounted to rotate with respect thereto, by means of a bearing member 7 (shown in detail in Fig. 6). The bearing member 7 is a circular disc which is struck-out of the side of the box and then reinserted to provide a bearing for the switch handle and the means by which the handle can operate the parts within the casing, at the same time providing a substantially water and dust-tight box. The switch handle has the usual member 8 for the manual operation. The handle 6 has on one end an offset portion 9 provided with locking holes 10. The casing carries adjacent the switch handle, a co-operating locking angle member 11, provided with locking holes 12 placed thereon in a position similar to the holes 10 in part 9. A padlock, or seal, or any suitable locking means can be passed through the co-operating holes 10 and 12 to secure the switch handle against operation when in the "off" position.

The casing has two chambers 13 and 14, separated by a partition 15 preferably of insulating material. The chambers 13 and 14 may be called the fuse and switch chambers, respectively. A base plate 16 of any suitable insulating material is fastened to the bottom of the casing and serves as the support for the binding posts, fuses, and switch mechanism.

The fuses 17 may be of the ordinary wire type or they may be of the enclosed type, and they connect binding posts 18 with switch plates 19. Opening of cover 3 gives access to the fuses 17 for the purpose of renewal or 95 inspection.

The switch mechanism is located in chamber 14 to which access may be had through the cover 4, the partition 15 preventing access through cover 3. The switch may be of the ordinary knife blade type, such as of blades 20 mounted pivotally on posts 19, and connected by insulating cross piece 21 for unitary operation. The blades 20 when in closed position engage with and form electrical connection with binding plates 22 (only one being shown). A U-shaped member 23, pivoted at the ends of the U to the casing by means of a rivet at one end and rigid connection with the "knock-out" bearing mem-

90

95

100

105

110

ber 7 at the other end, carries rigidly from the center of the U, an arcuate member 24. The arcuate member extends downwardly and adjacent the cross bar 21, and has a slot 25 in its lower part for the reception of a neck portion 26 of a member 27, carried by the cross piece 21 of the switch. The slot 25 acts as a guide for the member 27 due to the shoulders 28 and projections 29. The arcuate member 24 is connected to the member 27 by means of a spring 30 attached to hook 31 on member 24 and to hook 32 on member 27, thus forming a resilient connection between the two members 24 and 27, relative movement of the two members being limited by the slot 25.

shown in Fig. 3, the member is at the upper end of the slot 25. Movement of member 23 upwardly will not at once move the switch because of the slot 25. The spring 30 will be tensioned and when the tension becomes great enough to overcome the friction that is holding arms 20 in place, the switch will be snapped into "off", or open, position, as shown in Fig. 4. It will thus be seen that a quick breaking action is provided in order to reduce sparking to a minimum. When the switch parts are in the position shown in Fig. 4, the arm 33 and offset portion 34 are moved away from locking member 35 and permit of the opening of the cover 3.

When the switch handle 6 is moved to "on"

Also connected to the members 7 and 23 in position, the upper end of the slot 25 engages an arm 33 having an offset end 34 adapted to member 27 and forces the switch positively when the switch handle is in "on" position into closed position, and arm 33 moves at 65 to prevent movement of a locking member 35 the same time into locking position for the carried by the cover 3, so that the cover 3 covers 3.

cannot be opened, and adapted when the switch handle is in "off" position to clear locking member 35 and permit of the opening of the cover 3. The member 23 has one end offset, as at 36, to provide clearness for end 34 and member 35.

I claim:

A safety switch comprising a casing, an operating element disposed transversely of the casing and mounted for pivotal movement therein; an arcuate bar carried by said element and having a hook on its upper end

The cover 4 may carry indicia 37 to indicate the "off" and "on" positions of the switch. The lead wires enter the box and connect with contact plates 22 as at 38. Current is taken from the box through plates 18 by contacts 39 to which the wires are connected. element and having a hook on its upper end and an elongated aperture in its lower depending end; a switch arranged in said case 75 and having a controlling member mounted to oscillate between open and closed positions about an axis substantially the same as the axis of the element, a lug carried by the switch controlling member and 80

35 When the switch handle 6 is in the position shown in Fig. 2 the switch is closed and the parts are in the position shown in Fig. 3. The cover 33 cannot be opened to provide access to the fuse chamber 13 since the locking member 35, which is carried by the cover, will engage against offset end 34 on arm 33. If the switch handle is now moved to "off" position, parts 23 and 33 will be projecting radially therefrom, said lug passing through the bar and having a neck portion in said elongated aperture, said lug terminating at its free end in a hook, a spring connected between the hook on the lug and the hook on the bar, and means accessible from the exterior of the casing for shifting the operating element to operate the switch to either of its positions. 85

45 moved also into the positions shown in Fig. 4, since all are connected to bearing mem- 90
ber 7. When the parts are in the position
